CLAIM

(21) Appl. No.: **29/215,869**

The ornamental design for a component of a flat harmonic drive actuator, as shown and described.

(22) Filed: **Oct. 27, 2004**

DESCRIPTION

(30) **Foreign Application Priority Data**

Oct. 27, 2004 (JP) 2004-012698

FIG. 1 is a front, side perspective view of a component of a flat harmonic drive actuator showing our new design.

FIG. 2 is a rear, side perspective view thereof.

FIG. 3 is a front elevational view thereof.

FIG. 4 is a rear elevational view thereof.

FIG. 5 is a left side elevational view thereof; the right side being a mirror image thereof.

FIG. 6 is a top plan view thereof the bottom plan being a mirror image thereof; and,

FIG. 7 is a cross-sectional view taken generally along the line 7—7 of FIG. 3.
